SLICING MACHINE

Paul G. Peddicord, Dayton, Ohio, assignor, by
mesne assignments, to International Business
Machines Corporation, New York, N. Y., a cor-
poration of New York

Application February 1, 1930, Serial No. 425,184

12 Claims. (Cl. 146—102)

This case relates to food slicing machines.

In general, the object of this invention is to increase the efficiency and practicability of a slicing machine by improving the various parts thereof.

Specifically, an object of the invention is to provide a novel clamping means for holding and feeding an article to be cut by the knife.

Further and other objects and advantages will 10 be hereinafter set forth in the accompanying specification and claims, and shown in the drawings, which by way of illustration show what is now considered to be the preferred embodiment of the invention.

15 In the drawings:

Fig. 1 is a view of the machine from the feeding side.

Fig. 2 is an end view of the machine from the gage plate side.

20 Fig. 3 is a detail view of the clamp.

Fig. 4 is a detail view of the clamp and carriage.

Fig. 5 is a front view of the clamp.

25 Fig. 6 is a rear detail view of the carriage and clamp.

Fig. 7 is a view of a modified clamp, and

Figs. 8 and 9 are sections through lines 8—8 and 9—9 of Fig. 7, respectively.

Referring to the drawings in detail, the machine 30 comprises a base 10 on which is fixedly mounted a motor 11 and a box frame and knife housing 12. The front or motor side of the housing is provided with a hub portion 13 for journaling the shaft 15 of a pulley 16 carrying a disk 17 and driven by a belt 18 from a pulley 19 on the motor shaft. To the upper edges of frame 12, a cantilever beam or frame 20 is secured by screws 21. The rear or feeding side of the frame 12 is closed by a cover plate 22 removably secured to frame 12 by screws 23 and 25.

Grindstones 30 and 33 are provided to sharpen the knife, a cover 35 being used to shield stone 30 when in retracted, non-sharpening position.

The cantilever beam 20 at its unsupported end 45 has secured thereto by screws 50, a box housing and frame 51 for the gage plate mechanism. The support for the frame 51 is such that it is free of the base 10 and permits the slice receiving plate 52 carried by the base to extend beneath the frame. This makes it easier for the merchant to receive the slices, as his view is not obstructed as is the case when the gage plate housing is mounted directly on the base. It also provides a more sanitary construction, the plate 52 being 55 easily cleaned and there being no corners in

which meat particles or the like may accumulate. Further, the area of the receiving plate may be made much greater than when it is necessary to limit it by engagement with a gage plate housing rising from the base, thus permitting a greater number of slices to be received.

The front or motor side of the gage plate housing is formed with a hub portion 53 (see Figs. 1 and 2). In the hub portion is journalled a shaft 55 fast to a cam disk 56 having three similar circumferentially spaced cam surfaces 57. In engagement with each cam surface is a roller 58, each rotatably mounted between a pair of lugs 59 extending perpendicularly from the rear of a gage plate 60. Adjacent each corner of plate 60, a tube 61 is fixed thereto which is slidably guided on a rod 62 secured to the housing 51. Springs 63 between the heads 64 of the rod and the closed ends of the tubes 61 in which the rods are located normally urge the gage plate 70 towards the cam disk. Pinned to the exteriorly accessible end of the shaft 55 of the cam disk is a sleeve 65 carrying a handle 66 and a graduated segment 67. By grasping and turning the handle, the cam disk may be adjusted to present different portions of its cam surfaces to the rollers 58, the springs 63 causing the gage plate to follow the contour of the cam surfaces and move in a horizontal direction relative to the plane of the knife.

Mounted on the base in front of the gage plate and cover plate 22 are a pair of vertical posts 76 and 77 carrying between them a round rail 78. Below the latter is a flat rail 79 directly secured to the base. Rails 78 and 79 guide a carriage 80 for movement past the knife. The carriage is provided with a through opening 81 (Fig. 6) through which rail 78 passes and a guide lug 82 sliding on rail 79.

To ease the shock of engagement of the carriage with the posts 76 and 77, rubber or felt bumpers 83 are provided at each end of the carriage. Rigidly secured to the bottom of the carriage is a handle 84 by means of which the carriage may be moved. Secured to the right side of the carriage, as viewed in Figs. 1 and 4 is a rail 85, the upper and lower edges of which are V-shaped. A clamp 86 is guided on said rail 85 for movement to and from the plane of the gage plate and knife. The clamp comprises a casting rotatably carrying upper and lower V-shaped rollers 87 riding on the edges of rail 85. A spiked plate 88 is secured by hand screws 89 to a ledge 90 of the clamp. Between the plate 88 and the surface of the carriage a porcelain plate 110

- or tray 91 is immovably mounted on the carriage. Casting 86 carries for cooperation with plates 88 and 91 a spiked clamp plate 92 fixed to the end of a square rod 93. The upper end of the rod 5 is pivoted on a pin 94 fixed within a slot or recess 95 cut in the side of a bar 96. The latter is slidably mounted in an opening cut through the post 97 formed at the upper end of the casting 86. To limit the movement of rod 93 clockwise, as 10 viewed in Fig. 3, the end of the rod has a projection 98 which engages the inner end of a handle 99 secured to the bar 96. The contact of the side of the rod with the lower wall 100 of the recess 95 limits the movement of the rod in the opposite 15 direction.
- At its lower end, bar 96 is provided with a hole 101 in which is located a spring 102 (Fig. 5) bearing against a tab 103 formed on the end of a latch plate 104 extending at right angles to the tab. 20 The latch is pivoted to the bar 96 at 105 and normally tends under the force of spring 102 to move counterclockwise, as viewed in Fig. 5, this movement being limited by contact of the side of the latch with the bar 96. When the clamp plate 25 92 is in horizontal position for coaction with clamp plate 88, the lug 106 on the latch is located in front of the rod 93 preventing its accidental movement forward out of the recess 95. By pressing on the tab 103 against the force of spring 30 102, the lug 106 is displaced from the front of rod 93 and the latter may be moved out of the recess to position clamp plate 92 parallel to the gage plate 60 and permit it to serve as a pusher plate as indicated in Fig. 2 and in broken lines in Fig. 3.
- 35 The return movement of the latter clamp plate to horizontal position is prevented by contact between rod 93 and the top of lug 106. Post 97 is formed with a recess 107 in which is a spring 108 bearing on a dog 109 pivoted to the post. The upper end of the dog is adapted to enter a notch 110 in the bar 96 when the latter is in uppermost position and retain it in this position while an article is being placed on the carriage. By pressing on the tail of dog 109, the bar is released and 40 drops by gravity onto the article. The dog may be actuated by the thumb of the hand grasping handle 99. The latter is provided with a guard plate 111 shielding the hand gripping the handle from the knife during movement of the carriage 45 past the knife to slice an article.
- To guard the edge of the knife, a member 120 shaped to conform to the edge of the knife is fixed to the frame 12 between the knife and the receiving tray. The tray is cut away to the shape of 50 the guard member to permit removal of the tray at right angles to the plane of the guard member.
- The gage plate housing is capable of being supported solely by the cantilever beam 20 but to brace the housing an angular piece 122 is fixed at 55 one end to the post 76, extends horizontally from the post and then vertically below the housing 51 to which it is fixed. The shape of piece 122 is such that it does not obstruct the view of the merchant during cutting operations or interfere 60 with the reception of slices by the portion of the receiving tray to which it is adjacent. If desired, piece 122 may be omitted.
- Figs. 7, 8 and 9 show a modification of the 65 clamp carried by the reciprocatable carriage. In this modification the carriage 80' is provided at the side adjacent the gage plate, with a lug 135 tapped to receive the threaded end of a round rod 136. A nut 137 is threaded on the end of the rod so as to abut the side of lug 135 and thereby prevent 70 accidental movement of the rod. An arm 75

138 is provided with a sleeve 139 at one end fitting over rod 136. Rod 136 is tapped to receive a screw 140 between which and sleeve 139 is a friction disk 141, preferably of leather. The screw 80 may be adjusted to provide sufficient friction between the leather disk and the sleeve 139 to cause the clamp to stay in any adjusted pivotal position relative to the rod 136. The other end of the arm 138 is also provided with a sleeve 142 to receive the round rod 143 fixed to and extending 85 from a casting 144, which is similar to casting 86 in the first modification.

The rod is internally threaded at the near end to cooperate with a headed screw 145. Between the head of the screw and the end of the sleeve is a disk 146 pinned to the rod 143 and abutting the end of the sleeve and a spring washer 147 abutting the disk. By adjustment of the screw 145 more or less frictional pressure may 90 be set up between disk 146 and the adjacent end of sleeve 142 and between the other end of the sleeve and the thrust shoulder 148 of the rod 143.

Casting 144, similarly to casting 86 of the first modification is formed with a post 149 in which 95 is a square hole 150 to receive a square bar 151 pivotally carrying at its end a clamp plate 152. Post 149, bar 151, and clamp 152, are similarly constructed and cooperate as post 97, bar 96 and clamp 92 of the first modification.

While the invention has been disclosed as applied 100 to constructions hereinabove described, it will be understood that various changes within the scope of the invention may be made and applicant therefore desires to be limited only by the following claims.

110 I claim:

1. In a slicer, a knife, a gage plate substantially parallel to the knife, an article support, a carrier mounted on the support for movement towards the planes of the knife and plate, a clamp 115 having a gripping face and means for pivotally mounting the clamp on the carrier to move about an axis transverse to the direction of said movement of the carrier to alternatively present the gripping face towards the gage plate to clamp 120 end pieces or to present the gripping face towards the article support to act as a hold-down clamp.

2. In a slicer, a knife, an underlying article supporting device mounted to move in a direction 125 generally parallel to the cutting plane past the knife edge, and a member pivotally associated with and movable with the device and having a gripping face above said device, and a pivotal mounting for said member on which the latter is 130 pivotally adjustable relative to the device to position said gripping face substantially in a horizontal plane to clamp an article against said device and to alternatively position said gripping face substantially in a vertical plane to grip 135 an end piece.

3. In a slicer, a knife, an underlying article support, a carrier mounted to move in a direction generally parallel to the cutting plane past the knife edge, a device vertically slidably connected to said carrier, and a member having a gripping face and pivotally connected to said device, said member being pivotally adjustable to present the gripping face towards the knife plane for gripping an end piece or to present the self-same gripping face towards the article support for clamping an article against the support, and said device being vertically slidable to cause said gripping face when in the latter mentioned position to clamp different sizes of articles.

4. In a slicer, a knife, an abutment plate, an underlying article support to hold an article during the slicing operation, a clamp carrier movable towards the abutment plate, a clamp having a gripping face, and means for mounting said clamp on the carrier to adjust the gripping face into position confronting the support to clamp an article thereagainst during the slicing operation or to alternatively present the face towards the abutment plate to clamp an article thereagainst during the slicing operation, said mounting in any one position of the carrier locating the gripping face closer to the abutment plate when confronting the plate than when confronting the support.
5. In a slicer, a knife, an article support for holding an article to be cut by said knife, a device slidably mounted on the support for movement towards the cutting plane of the knife, a link pivoted at one end to the device to move vertically relative thereto, a guide member pivoted to the other end of the link, and a clamp slidably carried by the guide member to grip an article on the support during the cutting operation.
6. A slicing machine comprising a knife for slicing an article, a gage plate, and feeding means for the article including a carriage for holding the article and movable past said knife, a face plate, a carrier therefor movable on said carriage, and a pivotal connection between the face plate and carrier to permit the face plate to be moved from a position confronting the gage plate to coact with the latter for clamping the article on the carriage to a position confronting the carriage to coact with the latter in clamping the article.
7. A slicing machine comprising a knife for slicing an article, a gage plate; and feeding means for the article including a carriage for holding the article and movable past said knife, a face plate, a carrier therefor movable on the said carriage towards the gage plate, and a swingable connection between the carrier and face plate to permit the latter to be moved from a position confronting the gage plate to coact with the latter for clamping the article on the carriage to a position confronting the carriage to coact with the latter in clamping the article.
8. A slicing machine comprising a knife for slicing an article, a gage plate, and feeding means for the article including a carriage for holding the article and movable past the knife, a face plate, a carrier therefor movable on the carriage towards the gage plate, and a swingable connection between the carrier and face plate to permit the latter to move from a position confronting the gage plate to coact with the latter in clamping the article to a position confronting the carriage to coact with the latter in clamping the article, the face plate being arranged relative to the axis of its swinging movement to be located closer to the gage plate when moved to confront the latter than when confronting the carriage.
9. A slicing machine comprising a knife for slicing an article, a gage plate, and feeding means for the article including a carriage for holding the article and movable past the knife during the cutting operation, a face plate, a carrier therefor movable on the carriage towards the gage plate, and a pivotal mounting on the carrier for the face plate to mount the latter for movement about an axis parallel to the plane of the gage plate from a position confronting the gage plate to coact with the latter in clamping the article to a position confronting the carriage to coact with the latter in clamping the article.
10. In a slicing machine, a generally vertically disposed rotary disk knife, a cover plate for said knife, a gage plate at the side of the knife and substantially parallel to the cover plate, a carriage for holding an article, means for mounting the carriage to reciprocate along the gage plate, knife, and cover plate to cause the knife to cut a slice from the article on the carriage, a guide secured to the carriage, a clamp support having guiding engagement with said guide to move along the carriage towards the gage plate, knife plane, and cover plate, a vertically movable member carried by said clamp support to move towards and from an article supported on said carriage, a clamp element having a face for gripping an article on the carriage, a pivot on said vertically movable member arranged generally parallel to the planes of the gage plate, cover plate, and knife and by which said clamp element is pivotally and adjustably carried to present its face towards the carriage in a position to coact with the latter to clamp an article during the reciprocation of the carriage and to alternatively present the same face towards the gage plate and cover plate in a position to coact with each of the latter as an end piece clamp for the article on the carriage, co-acting means on the clamp element and said vertically movable member to locate the clamp element in each of its positions, and retaining means for holding the clamp element stationary relative to said vertically movable member in each of its alternative positions.
11. In a slicing machine, a knife, a gage plate at the side of the knife and substantially parallel to the cutting plane, a carriage for holding an article, means for mounting the carriage to traverse the gage plate and knife to cause the knife to cut a slice from the article on the carriage, a guide secured to the carriage, and clamping means comprising a member having engagement with the guide to move along the carriage towards the gage plate, a clamping element, and means for pivotally mounting the clamp on said member to turn relative to the member in an angular path transverse to the plane of the gage plate, to coact in one of its angularly adjusted positions with the carriage to clamp an article during the cutting operation and to coact in another of its angularly adjusted positions with the gage plate as an end piece clamp for the article on the carriage.
12. In a slicing machine, a knife, a gage plate, a cover for said knife leaving a cutting edge of the latter exposed, a carriage for holding an article to be sliced, said carriage and knife being relatively movable past each other to cause the knife to cut a slice from the article, a face plate for gripping an article, and supporting means cooperatively associating the face plate and carriage for supporting the face plate with its gripping face presented towards the carriage to coact with the latter to grip an article on the carriage during the slicing operation and for alternatively supporting the face plate with the same gripping face confronting the gage plate and cover to coact with each of the latter as an end piece holder for an article on the carriage during the slicing operation.

PAUL G. PEDDICORD.
